US0D1043583S

(12) **United States Design Patent** (10) Patent No.: **US D1,043,583 S**
(45) Date of Patent: ** Sep. 24, 2024

(54) **CONNECTOR**

(71) Applicant: **Molex, LLC**, Lisle, IL (US)

(72) Inventors: **Michael A. Bandura**, Naperville, IL (US); **Venkatesh Sathish**, Bengaluru (IN); **Jeffrey Alan Joniak**, Homer Glen, IL (US)

(73) Assignee: **Molex, LLC**, Lisle, IL (US)

(**) Term: **15 Years**

(21) Appl. No.: **29/886,209**

(22) Filed: **Mar. 6, 2023**

(51) LOC (14) Cl. **13-03**

(52) U.S. Cl.

USPC **D13/133**

(58) **Field of Classification Search**

CLAIM

The ornamental design for a connector, as shown and described.

DESCRIPTION

FIG. 1 is a front top perspective view of a connector showing our new design;

FIG. 2 is a front bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The uneven-length broken lines immediately adjacent to the shaded area defines the bounds of the claimed design and forms no part thereof. The even-length broken lines depicting the remainder of the connector form no part of the claimed design.

1 Claim, 8 Drawing Sheets
